UNITED STATES PATENT OFFICE.

ROBERT B. SMITH, OF QUINCY, MASSACHUSETTS, ASSIGNOR TO UNITED SHOE MACHINERY COMPANY, OF PATERSON, NEW JERSEY, A CORPORATION OF NEW JERSEY.

MACHINE FOR SETTING EYELETS OR THE LIKE.

1,176,867.

Specification of Letters Patent. Patented Mar. 28, 1916.

Application filed January 17, 1910. Serial No. 538,459.

To all whom it may concern:

Be it known that I, ROBERT B. SMITH, a citizen of the United States, residing at Quincy, in the county of Norfolk and State 5 of Massachusetts, have invented certain Improvements in Machines for Setting Eyelets or the like, of which the following description, in connection with the accompanying drawings, is a specification, like reference 10 characters on the drawings indicating like parts in the several figures.

This invention relates to machines for setting eyelets or other fastening devices in sheet material and particularly to that 15 class of machine having punching devices arranged to perforate the work and coöperating setting devices arranged to insert and clinch an eyelet or the like in the previously punched hole.

20 An object of this invention is to provide a machine having an improved organization and arrangement of punching and setting instrumentalities.

To this end an important feature of the 25 invention consists in the combination with a punch of a sectional punching die movable relatively to the punch with its sections locked together to effect the punching operation, and setting dies relatively movable to insert and clinch a fastener, in the work so punched. The provision of locking means for the sectional die insures the maintenance of the complete contour of the die when the punching operation takes place 30 and consequently that the work shall be cleanly perforated.

Another feature of the invention consists 40 in a punching and fastener setting machine having a sectional punching die of which the sections are arranged for independent adjustment. Such construction facilitates the accurate positioning of the parts in assembling the machine and permits compensation for wear or convenient adjustment for other purposes while the machine 45 is in use.

The invention also contemplates the employment, in a punching and fastener setting machine, of novel mechanism for advancing a punching die toward a punch for forcing the work against the punch to perforate the work and for holding the die

against further longitudinal movement. As herein shown, this mechanism includes a crank and link connection disposed to reach 55 a dead point at the conclusion of the punching operation and so hold the die against further movement upon the punch.

The invention also contemplates the employment, in a punching and fastener setting machine, of a carrying member for the punching die which member is provided with ways for a movable separating device for the die sections. This arrangement is 60 advantageous from a structural standpoint 65 since the ways may be formed in the carrying member more easily than they could be formed in the interior of the machine frame.

Still another feature of the invention consists in a punching and fastener setting machine having a work table or plate located in a position wherein its surface is substantially flush with the sections of the punching die when the latter is in its initial position. Such construction affords a continuous 70 supporting surface upon which the work may be moved in all direction and located with accuracy for the reception of the fastener. 75

Other features of the invention, including 80 important combinations of parts and details of design and construction, will be herein-after more specifically described and claimed.

85 Reference is to be had to the accompanying drawings in which:

Figure 1 is a side elevation; Fig. 2 is a view in perspective of the working parts of the machine as located prior to the punching operation, the work table being removed; Fig. 3 is a similar view of the working parts as located after the punching operation; Fig. 4 is a view in perspective showing the operating connections of 90 the lower setting die and the punching die; Fig. 5 is a plan view of the work table. 95

Before proceeding to a detailed description of the machine it will be convenient to state briefly its mode of operation and the 100 general arrangement of its working parts.

The machine comprises a frame 2 carrying a stationary punch 4 and upsetting die 6. Mounted in the frame 2 for movement

toward and away from said punch 4 is a sectional punching die comprising the plates 10 normally located in the plane of the work table 62 upon which the work to be 5 eyeleted is placed. When the treadle rod is actuated the die plates are raised through suitable toggle mechanism and the work is forced against the punch and perforated. During this operation the lower setting die, 10 which is located beneath the punching die, has extracted an eyelet from the raceway 38 and immediately after the punching operation the sections of the die plate are separated by a wedge bar 27 and the lower setting die emerges carrying the eyelet which 15 is threaded on the punch 4, forced through the work and finally clenched against the upsetting die 6. The lower setting die is then retracted and the sections of the die 20 plate are moved together and downwardly thus allowing the eyeleted work to be removed from the punch.

The frame 2 of the machine is of suitable shape to support the working parts at a 25 slight forward inclination to the vertical which arrangement has been found to be the most convenient for an operator. In the upper branch or jaw of the frame is adjustably mounted a normally stationary punching and upsetting device comprising the centrally disposed punch 4 and annular upsetting die 6. These devices may be adjusted in any preferred manner, for example, by means of an adjusting nut 7, and a set 30 screw 8 is provided for locking them in any adjustable position. The end of the punch 4 is made square except for a small central projection 9 which serves to force the punching through the die plate.

40 The die which co-operates with the punch 4 is formed by two plates 10 in each of which is formed a recess which constitutes one half of the die. The contacting edges of the plate are cut away except adjacent 45 the die-forming recesses in order to insure a more perfect fitting together of the plates. Each of the plates 10 is adjustably mounted in a holder 12, being slotted for the reception of the screws 11, and by loosening these 50 screws opportunity is afforded for shifting the plates 10 to bring the recesses into registration or to bring the die so formed into alignment with the punch 4. The holders 12 each consist in a transversely extending 55 portion and a downwardly extending shank which is pivoted by a pin 13 to the plate 14 forming part of a square plunger 16. The upper surfaces of the holders 12 are recessed so as to receive the die plate 10 with 60 their upper surfaces substantially flush with the surfaces of the holders, in this way forming a substantially continuous work supporting surface when the die is in operative position. The inner faces of the shanks of 65 each holder are beveled off below the pivots

13 in order to allow the lower ends to approach each other as the upper portions of the holders are swung away from each other and a compression spring 18 is located between lower ends of the holders which serves 70 normally to maintain the holders with the die plates in operative relation. A stop pin or stud 20, extending through the plate 14 and into the inner wall of the plunger 16 is arranged to fit into recesses formed in the 75 adjacent faces of the holders 12 and determine independently the operative position of each holder, the holders being maintained in engagement with the pin 20 by the spring 18.

80 A locking clamp 22 is provided for positively locking together the holders until after the punching operation. The clamp comprises two side pieces, arranged to engage frictionally with the sides of the 85 holders 12, and a connecting plate to which is rigidly secured a downwardly projecting T-shaped member 23 the head of which is received in a correspondingly shaped slot 24 in the frame of the machine. The arrangement is such that as the plunger 16 is elevated carrying the holders 12 toward the punch 4, the clamp 22 is carried up with the holders until the head of the T-shaped member 23 engages the top of the slot 24 90 which occurs after the punching die has been forced on the punch 4 for a sufficient distance to punch a clean hole in the work. The upward movement of the plunger continues, however, and the holders then slide 95 upwardly through the clamp 22 until the pivots 13 are carried above the side pieces of the clamps, as shown in Fig. 3, in which position the holders are free to move apart against the pressure of the spring 18. The outer surfaces of the holders may be notched 100 and rounded to facilitate the spreading movement, as indicated in Fig. 4.

In order to separate the holders and punching die sections after the punching 110 operation a bar 26 having a wedge or spear point 27 is mounted for reciprocation in ways formed in the plunger 16 and is connected with actuating means which elevate it at the time when the plunger has reached 115 its highest point and is locked against further movement by the links of its straightened actuating toggle 56, 58. When the bar 26 is elevated its wedge shaped end is forced between the horizontally extending portions of the holders 12, which are slightly rounded at their adjacent lower edges in order to allow the wedge to enter between them, thus causing them to separate 120 and move apart.

125 A cylindrical plunger 30 is mounted for reciprocation in the lower jaw of the frame in alignment with the stationary punch and upsetting die 6, and carries the adjustably mounted lower setting die 32 which is pro- 130

vided with a yieldingly mounted center spindle 34 for the purpose of extracting an eyelet from the delivery end of the raceway and carrying it to the upsetting die. At its 5 lower end the plunger 30 is forked and connected with a link 36 forming a part of the actuating toggle to be described hereinafter. The raceway 38 is supported on levers 40 and 42 which are pivoted to the frame at 10 43 and 44. The lever 42 has two spaced rollers arranged to be engaged by the upper and lower engaging faces of an arm 47 which projects from the rear side of the toggle link 36. In normal position the 15 delivery end of the raceway 38 stands in the path of the center spindle 34, such position being regulated by the adjustable stop 48 which encounters an abutment on a rearwardly projecting arm of the lever 42. 20 When the arm 47 is moved upwardly its upper engaging face acts upon the upper of the two rolls carried by the lever 42 and moves the raceway rearwardly, after the plunger 30 has been elevated slightly to 25 cause the spindle 34 to impale the lowermost eyelet in the raceway. The lowermost eyelet is thus drawn out of the raceway and the latter moved to an inoperative position. On downward movement of the arm 47 the 30 lower engaging face acts on the lower roller of the lever 42 and moves the raceway forwardly to its normal position. The mechanism above described for operating the raceway is substantially similar to that disclosed 35 and claimed in United States Patent No. 898,729 granted September 15, 1908 to J. F. Davey.

The working parts of the machine are actuated by a treadle rod 50 through a lever 40 52 and a system of toggle links. Of these, the link 37 is pivoted to the inner end of the lever 52 and link 36 is pivoted to the lower end of the plunger 30, as shown in Fig. 4. A radius link 54 fast to the rock 45 shaft 55 is pivotally connected to the knuckle of the toggle and serves to guide its motion in an arc about the rock shaft as center. The rock shaft 55 projects through one side of the frame and on its outer end is provided 50 with a crank arm 56 which is connected with the squared plunger 16 through the medium of a link 58 and stud 59. Another link 60 is also pivoted to the knuckle of the toggle 36, 37 and this link is connected with 55 and actuates the separating bar 26.

The toggle and the various connecting links are so proportioned and arranged that, on downward movement of the treadle rod 50 the plunger 16, the bar 26 and the plunger 30 are all elevated at about the same rate at first. The arm 56 and link 58, which it will be observed, constitute an independent toggle in themselves, are soon brought 60 into alinement and the upward movement 65 of the holders 12 and punching die there-

fore ceases. The upward movement of the bar 26 and plunger 30, however, continues until the toggle links 36, 37 and the forward end of the lever 52 are brought into alinement and this latter movement, as already 70 explained, results first in the separation of the halves of the punching die and then in the setting movement of the lower setting die.

The treadle rod 50 is moved upwardly to 75 retract the plungers by a spring, not shown, and is limited in this movement by an adjustable stop 51 on the lever 52 which engages with a fixed abutment on the frame of the machine. On the upward movement of 80 the treadle rod 50 the lower setting die 32 and the rod 26 are quickly retracted and the holders 12 are allowed to close under the actuation of the spring 18. During this movement the toggle 56, 58 is on or near its 85 dead point and accordingly little or no movement is transmitted to the plunger 16 until the lower setting die and the separator bar 16 have been retracted.

A hopper 70 for eyelets is mounted upon 90 the rear end of the raceway 38 and is provided with an agitator of any usual type preferably a brush having a downwardly extending spindle upon which is fastened a forked arm 71 which engages a stationary 95 stud 72 on the frame of the machine. It will be seen that as the raceway and hopper 70 are moved back and forth the arm 71 and consequently the agitating brush will be oscillated and the eyelets will be brushed 100 out through the delivery ports to the raceway.

A work plate 62 is mounted on the front of the frame 2 by means of an angle bracket 64 and is arranged to surround the punching 105 die plates and form a continuous surface therewith when the latter are in their lowermost position, as shown in Figs. 1 and 5. At the rear of the punching die the work plate is slotted and a gage 66 is adjustably mounted in said slot by the aid of which the position of the work with respect to the punch made be accurately determined. Other gages may be provided if it is desired to locate the 110 work with a greater degree of accuracy. 115

In the foregoing description the rod 50 has been described, for the sake of clearness, as a treadle rod, but it will be obvious that it is immaterial by what means this rod is actuated and it is within the scope of the invention to drive the machine from any desired source of power. It will also be apparent that, with slight modifications in detail, the machine may be adapted for setting other fasteners than eyelets, such as lacing 120 hooks, rivets, studs, or similar articles. The employment of the machine for setting such articles is contemplated by the present invention and is within the scope thereof. 125

Having described my invention, what I 130

claim as new and desire to secure by Letters Patent of the United States is:—

1. A machine for setting fasteners in sheet material having, in combination, a stationary punch, a carrier arranged to reciprocate in a path at one side of the axis of the punch, relatively movable die holders mounted on the carrier and having offset portions, a reciprocatory setting device disposed normally at one side of the holders and beneath their offset portions, coöperating die sections mounted in the offset portions of the holders, and a separating device mounted in the carrier and movable relatively to the holders.

2. A machine for setting fasteners in sheet material, having in combination, a frame, a stationary punch and annular upsetting die mounted therein, a reciprocatory plunger, a setting die carried thereby, a second reciprocatory plunger, pivoted holders mounted thereon, sectional punching die plates adjustably mounted on said holders, and actuating mechanism for reciprocating said plungers and separating said sectional die plates.

3. A machine for setting fasteners in sheet material, having in combination, a frame, a stationary punch and annular upsetting die mounted therein, a setting die mounted for reciprocation toward and from said upsetting die, a reciprocatory plunger, pivoted holders mounted thereon, sectional punching die plates adjustably mounted on said holders, and actuating mechanism for reciprocating said setting die and said plunger and for separating said sectional die plates.

4. A machine for setting fasteners in sheet material, having in combination, a frame, a stationary punch and annular upsetting die mounted therein, a setting die mounted for reciprocation toward and from said upsetting die, pivoted holders mounted for reciprocation toward and from said punch, sectional punching die plates adjustably mounted on said holders, and actuating mechanism for reciprocating said setting die and said holders and for separating said sectional die plates.

5. A machine for setting fasteners in sheet material, having in combination, a frame, a stationary punch and upsetting die mounted therein, a setting die mounted for reciprocation toward and from said upsetting die, and a sectional punching die comprising relatively adjustable sections, said punching die being mounted for reciprocation toward and from said punch and means for dividing said punching die.

6. A machine for setting fasteners in sheet material, having in combination, a punch, an upsetting die concentric therewith, a sectional punching die comprising relatively adjustable sections, means for moving said punching die in a straight line path toward

said punch to effect the punching operation, and a setting die arranged for reciprocation between the sections of said punching die.

7. A machine for setting fasteners in sheet material, having in combination, a punch, an upsetting die concentric therewith, a sectional punching die comprising independently adjustable sections, means for moving said punching die in a straight line path toward said punch to effect the punching operation, a setting die, means for separating the sections of said punching die, and means acting after such separation for advancing said setting die toward the upsetting die.

8. A machine for setting fasteners in sheet material, having in combination, a punch, a coöperating punching die comprising relatively movable sections, means for rigidly locking said sections together, mechanism for moving said punching die toward said punch to perforate the work, and means for inserting a fastener in the hole so formed.

9. A machine for setting fasteners in sheet material, having in combination, a punch, a coöperating punching die comprising relatively movable sections, means for rigidly locking said sections together, mechanism for moving said punching die toward and into punching relation with said punch, said mechanism being arranged to hold the punching die against movement longitudinally of said punch on the completion of the movement in which the punching operation is effected, and means for inserting a fastener in the hole so formed.

10. A machine for setting fasteners in sheet material, having in combination, a punch, a coöperating punching die arranged to occupy an initial position remote from the punch, mechanism for moving said punching die toward and upon said punch, said mechanism being arranged to hold the punching die against movement longitudinally of said punch after the completion of the movement in which the punching operation is effected, and coöperating setting devices constructed and arranged to be subsequently operated.

11. A machine for setting fasteners in sheet material, having in combination, a punch, a coöperating punching die, actuating means for moving the die, a crank and link connection between said die and its actuating means arranged to move said die upon said punch and to hold it rigid against movement longitudinally of said punch, and coöperating setting devices constructed and arranged to be subsequently operated.

12. A machine for setting fasteners in sheet material, having in combination, a punch, a coöperating punching die arranged to move in a path parallel to the axis of the punch and comprising relatively movable sections, relatively movable locking means

arranged to lock said sections rigidly together in one position but permitting relative movement thereof in another position, and setting tools operative when the die sections are unlocked.

13. A machine for setting fasteners in sheet material, having in combination, a punch, a coöperating punching die comprising relatively movable sections, locking means therefor, means for moving said die in a direction parallel to the axis of the punch into punching relation with said punch, said means causing said locking means to become inoperative after the punching operation, and setting tools operative when the die sections are unlocked.

14. A machine for setting fasteners in sheet material, having in combination, a punch, a coöperating punching die comprising relatively movable sections, locking means therefor, actuating means for said die, a crank and link connection arranged to move said die into punching relation with said punch, and thereafter to cause said locking means to become inoperative, and setting tools operative when the die sections are unlocked.

15. A machine for setting fasteners in sheet material, having in combination, a punch, relatively movable holders, sections forming a coöperating punching die mounted therein, means acting on said holders for rigidly locking said sections together, mechanism for moving said punching die toward said punch with its sections locked together to perforate the work, and means for inserting a fastener in the hole so formed.

16. A machine for setting fasteners in sheet material, having in combination, a punch, relatively movable holders, sections forming a coöperating punching die mounted therein, means acting on said holders for locking said sections together, and means for moving said punching die toward and into punching relation with said punch to perforate the work, said mechanism being arranged to hold the punching die against movement longitudinally of said punch after the completion of the movement in which the punching operation is effected, and means for subsequently inserting a fastener in the work so punched.

17. A machine for setting fasteners in sheet material, having in combination, a punch, relatively movable holders having shanks extending substantially vertically and portions extending substantially horizontally, sections forming a punching die mounted therein, locking means acting on the shanks of said holders for locking said sections together, means for moving said punching die to effect the punching operation, and coöperating setting tools.

18. A machine for setting fasteners in sheet material, having in combination, a

punch, holders pivoted for relative movement toward and away from each other, sections forming a punching die mounted in said holders, means operative after the punching operation for separating said 70 holders, a device for locking said holders together prior to the punching operation, and means for subsequently inserting a fastener in the punched work.

19. A machine for setting fasteners in sheet material, having in combination, a punch, holders pivoted for relative movement, plates forming a punching die mounted in said holders and arranged to be held thereby with their edges in contact, means 80 for moving said die upon said punch, and thereafter for holding said die against movement longitudinally of said punch, means for engaging and separating said holders when held in this condition, and 85 means for subsequently inserting a fastener in the punched work.

20. A machine for setting fasteners in sheet material, having in combination, a punch, holders arranged for relative movement, sections forming a punching die mounted in said holders, means for moving said die upon said punch to punch the work and thereafter for holding said die against further movement, means for engaging and 95 separating said holders when held in this condition, and tools for subsequently setting a fastener in the punched work.

21. A machine for setting fasteners in sheet material, having in combination, a 100 punch, holders arranged for relative movement, sections forming a punching die mounted in said holders, means for positively separating said holders, yielding means for moving said holders together, a 105 single clamping device for engaging both holders and positively preventing the separation of said holders during one part of the cycle of the machine, and setting tools operative during another part of the cycle. 110

22. A machine for setting fasteners in sheet material, having in combination, a punch, a coöperating punching die comprising separable sections, holders for said sections, a clamp shaped to embrace the holders 115 and normally preventing relative movement thereof, means for moving said holders relative to said clamp to render said clamp inoperative, and setting tools subsequently operative.

23. A machine for setting fasteners in sheet material, having in combination, a punch, a coöperating punching die comprising separable sections, holders for said sections, a clamp normally preventing relative 125 movement thereof, means arranged to move said holders and said clamp simultaneously while the holders are locked together, means for arresting the movement of said clamp whereby it may be rendered inoperative 130

- after a predetermined movement, and setting tools subsequently operative.
24. A machine for setting fasteners in sheet material, having in combination, a punch, a coöperating punching die comprising separable sections, pivotally mounted holders therefor, a clamp arranged to engage said holders at a distance from their pivots, means for causing relative movement of the holders and clamp to bring the clamp opposite the pivotal points of the holders at a predetermined point in the cycle of the machine, and setting tools subsequently operative.
25. A machine for setting fasteners in sheet material, having in combination, a setting device, a punch, a coöperating punching die comprising separable sections, means for rigidly locking said sections together, mechanism for moving said punching die toward said punch to punch the work, and mechanism for subsequently actuating said setting device to clinch an eyelet or the like.
26. A machine for setting fasteners in sheet material, having in combination, a punch, a coöperating punching die comprising separable sections movable toward the punch in a direction parallel to the axis of the punch, separating means movable in the same direction, setting devices, actuating mechanism including a toggle, and connections therewith arranged for successively actuating said punching die, separating means, and setting devices.
27. A machine for setting fasteners in sheet material, having in combination, setting devices, punching devices including a punching die comprising relatively movable plates, means for elevating said punching die to punch the work, and a work plate arranged in the plane of said movable die plates when the punching die is in its lower position and constituting therewith a substantially continuous work support.
28. A machine for setting fasteners in sheet material, having in combination, punching devices including a sectional punching die, separable holders having laterally extending portions for said sections, and downwardly extending shanks, setting devices mounted in alinement with said punching die, and a single separating device acting on both of said holders at a point between said die sections and said shanks.
29. A machine for setting fasteners in sheet material, having in combination, punching devices including a sectional punching die, setting devices, a single clamp shaped to embrace a part of both sections for locking said sections together, and a member to control the action of said clamp.
30. A machine for setting fasteners in sheet material, having in combination, punching devices including a sectional punching die, holders for the sections of said die, a reciprocatory carrier upon which said holders are separably mounted, a separating device guided in said carrier, and coöperating setting devices.
31. A machine for setting fasteners in sheet material, having in combination, punching devices including a punch and a sectional punching die, relatively movable holders for the sections of said die, means for moving said sections toward said punch to perforate the work and then away from each other, then toward each other and finally away from said punch, and means for inserting a fastener in the hole formed by the punching devices.
32. A machine for setting fasteners in sheet material, having in combination, punching devices including a punch, a punching die comprising plates having complementary recesses, holders for said plates having also complementary recesses, means coöperating with the recesses in said holders to determine the positions of the recesses in said plates, and coöperating setting tools constructed and arranged to operate in axial alinement with the punch.

In testimony whereof I have signed my name to this specification in the presence of two subscribing witnesses.

ROBERT B. SMITH.
